UNITED STATES PATENT OFFICE

JOHN W. BLACKLOCK, OF BROOKFIELD, MISSOURI

GRAVE COVER AND CASKET OR VAULT DECORATION

Application filed July 9, 1928. Serial No. 291,291.

This invention relates to combined grave covers and vault or casket decorations and aims to provide a novel, simple and inexpensive device adapted for disposition upon a 5 vault or casket before the same is lowered into the ground and that is for the purpose of receiving flowers, artificial grass or moss and that is adapted to rest upon the edges of the grave at the time of lowering the vault 10 or casket therein so as to cover the upper end of the grave until such time as it is necessary to fill the dirt into the grave.

In the drawing wherein like reference characters indicate corresponding parts 15 throughout the several views:

Figure 1 is an end elevation of a vault or casket arranged above the grave before its being lowered therein and upon which is arranged the present device, and

20 Figure 2 is a bottom plan view of the device.

Now having particular reference to the drawing, my novel invention consists of a steel wire frame preferably consisting of 25 three sections each being designated by the reference character 5. These frames consist of spaced lengths of wire, preferably steel wire and being joined or connected at their opposite ends by cross wires 6—6.

20 These sections are arranged in predetermined spaced relation interconnected by a chain length 7. Each section is bowed in a longitudinal direction and the longitudinal wires of the sections are formed adjacent 35 their opposite ends with downturned portions to provide feet or legs 8 having a suitable covering 9.

These feet or legs are adapted to support the frame upon and in slight spaced relation 40 with the casket or vault A. Arranged upon the convex side of the frame comprising said sections and secured thereto if desired is a wire or canvas matting 9 adapted to have arranged thereon artificial grass, moss or 45 flowers or the like B. The width of the de-

vice is greater than that of the coffin or vault A so as to completely cover the top thereof and to cause the engagement of the opposite longitudinal edges of the device as well as the end edges thereof with the edges 50 of the grave when the vault or casket is lowered for closing the upper end of the grave and to give the same a beautifying appearance until the attendants at the funeral have departed after which the device can 55 be removed and the grave filled in.

It will thus be seen that I have provided a highly novel, simple, and extremely useful device that is well adapted for all of the purposes heretofore designated.

Even though I have herein shown and described the invention as consisting of certain detail structural elements, it is nevertheless to be understood that minor changes may be made therein without affecting the 65 spirit and scope of the appended claims.

Having thus described my invention, what I claim as new is:

1. A flower holder and grave cover of the character described comprising a plurality 70 of longitudinally curved rectangular sections, each section including spaced parallel longitudinal bars and transverse end bars connecting the opposite ends of the longitudinal bars, said longitudinal bars being provided, 75 at points spaced inwardly from their opposite ends, with downturned substantially U-shaped portions constituting legs for supporting the sections in vertical spaced relation on a coffin lid and flexible elements for 80 connecting the sections together.

2. A flower holder and grave cover of the character described comprising longitudinally curved sections and supporting legs extending downwardly from said sections at 85 points spaced inwardly from the opposite ends thereof for engagement on the lid of a coffin or vault for supporting the sections in vertically spaced relation thereon.

3. A flower holder and grave cover of the 90

character described comprising a plurality of longitudinally curved sections, supporting legs extending downwardly from said sections at points spaced inwardly from the opposite ends thereof for engagement on the lid of a coffin or vault for supporting said sections in vertically spaced relation thereon, and flexible coupling elements for connecting the sections together.

10 In testimony whereof I affix my signature.
JOHN W. BLACKLOCK.
